FOOT-REST FOR A HIGH CHAIR OR THE LIKE

Louis Gottfried and Jacob Berger, New York, N.Y.

Application September 16, 1958, Serial No. 52,659

Term of patent 14 years

(Cl. D15—1)

FIG. 1.

FIG. 4.

FIG. 2.

FIG. 5.

FIG. 3.

FIG. 6.

Figure 1 is a front elevation of the foot-rest for a high chair or the like, showing our new design;

Fig. 2 is a top plan view thereof;

Fig. 3 is a rear elevation thereof;

Fig. 4 is an end elevational view;

Fig. 5 is an end elevational view but showing the adjustable element in another position; and

Fig. 6 is a front perspective view thereof.

The broken lines of Figure 1 are shown for illustrative purposes only.

We claim:

The ornamental design for a foot-rest for a high chair or the like, as shown and described.
